UNITED STATES PATENT OFFICE.

CHARLES W. L. HAYWARD, OF EAST WEYMOUTH, MASSACHUSETTS.

IRONING-TABLE.

SPECIFICATION forming part of Letters Patent No. 289,097, dated November 27, 1883.

Application filed July 18, 1882. (Model.)

To all whom it may concern:

Be it known that I, CHARLES W. L. HAYWARD, of East Weymouth, county of Norfolk, and State of Massachusetts, have invented an improvement in Ironing-Boards, of which the following description, in connection with the accompanying drawings, is a specification.

My invention relates to an apparatus for ironing; and it is embodied in an apparatus consisting of a convenient folding stand adapted to support ironing-boards of different sizes.

The apparatus also preferably comprises a compound ironing-board made of two separable portions, one of which, taken alone, forms a complete board of small size, suitable for ironing small tubular garments or tubular portions of garments—such as sleeves. The two portions of the board when placed together lie in one plane and form a board of large size—such as commonly employed for ironing skirts and large tubular garments. The stand consists of a main standard having a broad base, (shown as formed by two diverging legs,) and provided with a brace to engage a projecting tongue on the ironing-board and hold it out as an arm substantially at right angles to the said standard. A folding leg or support consisting of three portions jointed together is adapted, according to the way the said portions are arranged, to form a support for the larger or smaller board, as may be desired. The standard is provided with a bracket or shelf to hold an iron, and the said bracket, brace, and supporting-leg for the board are all hinged or jointed to fold parallel with the main standard, so that the entire apparatus occupies but small space when not in use. If desired, different-sized boards may be employed with the stand; but, as herein shown, a compound board is employed, consisting of a smaller portion of suitable size for the smallest board to be used, and having a tongue to be engaged and held by the main standard and its brace. Another portion, fitted to encircle and surround the smaller portion, is provided with cross-pieces to engage the said smaller portions and retain both portions in one plane, so that they serve to form a board of large size. The larger or outer portion may be removed from or applied to the smaller portion without disengaging the

latter from the standard, and the folding leg will be changed according as it is to support the smaller portion of the board alone or both portions together. 55

Figure 1 is a side elevation of an ironing apparatus embodying this invention, it being shown in full lines arranged to afford the largest-sized board, and in dotted lines for the 65 smaller-sized board; Fig. 2, a front view of the stand when folded; and Figs. 3 and 4, top and under side views, respectively, of the compound board detached from the stand.

The standard *a* may have a pedestal, *a'*, and 65 is provided with legs *b*, affording a wide base; has in its upper end an opening or socket, *c*, (see dotted lines, Fig. 2,) to receive a tongue, *d*, of the ironing-board *e*, and is also provided with a brace, *f*, engaging a small projection, 70 *g*, at the end of the said tongue, thus fastening the board *e* about at right angles to the standard *a*, the said standard, board, and brace being secured in this position by a key, *h*, entering a socket, *i*, in the said board. The 75 brace *f* is hinged or pivoted at 2, to fold up by the standard *a* when the apparatus is not in use. A bracket or shelf, *j*, preferably faced with asbestos-paper, (indicated by the heavy top line, Fig. 1, and the lozenge-work, Fig. 2,) 80 to hold a flat-iron, is pivoted or hinged at 3 to the standard *a*, so as to fold down beside it, as in Fig. 2, or to be held by the hook *k* in horizontal position when the apparatus is in use. The end of the ironing-board *e* is supported by the folding leg, consisting of the three portions *l m n*, the former hinged at 4 to the standard *a*, so as to fold parallel therewith, or to extend diagonally down therefrom to the floor, as shown in Fig. 1, a suitable 85 shoulder, *o*, limiting its movement in this direction, and a hook, *o'*, being employed to fasten it. The portion *m* is hinged to the portion *l* at 5, and when used with a large ironing-board extends along the floor, while 90 the portion *n*, hinged to the portion *m* at 6, stands vertical to support the board near its end, it being preferably fastened thereto by the hook *p*. A hook, *r*, is shown, by which the portions *m n* may be fastened in proper 95 relative position. When the stand is to be used for a smaller board, the portion *m* is turned up vertically, as shown in dotted lines, 100 Fig. 1, and the portion *n* extends down there-

from and is fastened to the under side of the board, as by the hook r . When the apparatus is not in use, the portion n folds wholly upon the portion m , the latter upon the portion l , and the three thus folded together turn down beside the standard a , the lower cross-piece, a' , of which has a suitable recess to receive them. The portion n may have feet n' n'' , if desired, to afford a larger bearing-surface. The board e , having the tongue d for attachment to the standard a , is provided with an eye, r' , in its under side, to receive the hook r of the portion n of the folding leg or support. If desired to use a larger board, the one e might be removed and a larger one having a similar tongue, d , employed in place of it; but the more convenient way is to employ a portion, e' , of the size desired for the larger board, it having a portion removed to exactly fit the board e , so that the two portions e e' , taken together, will form a compound board of large size, adapted to be supported by the standard a and folding leg l m n . The outer portion, e' , is provided with one or more cross-pieces, t , at its under side, extending across the recess in which the other portion, e , is received, and serving to support the said portion e , with its upper surface even with that of the portion e' . Another cross-piece, u , near the end of the portion e' , at its upper side, supports the said portion e' upon the portion e , near where the latter is itself supported on the

standard. When the two portions are used, they may be fastened together by the hook w , the larger portion e' being provided with an eye, p' , in its under side, to co-operate with the hook p of the portion n of the folding leg. 35

I claim—

1. The ironing-board and its supporting-stand, consisting of a standard adapted to support one end of the said board, combined with the folding leg composed of three portions hinged together and to the standard, as described, whereby they form a support at greater or less distance from the said stand- 45 ard, as and for the purpose set forth.

2. The ironing-board e and the supplemental board e' , connected therewith, substantially as shown and described, combined with its supporting-stand, consisting of a standard 50 adapted to support one end of the said board, and the folding leg composed of three portions hinged together and to the standard, as set forth, whereby they form a support a greater or less distance from the said stand-ard, as and for the purpose specified. 55

In testimony whereof I have signed my name to this specification in the presence of two subscribing witnesses.

CHARLES W. L. HAYWARD.
